Attorney

UNITED STATES PATENT OFFICE.

FLOYD M. LEWIS, OF PASCAGOULA, MISSISSIPPI.

PLUMB BOB.

Application filed January 13, 1927, Serial No. 160,861. Renewed June 25, 1928.

My invention relates to plumb bobs, and has for one object to provide a plumb bob adapted to be used in connection with a metallic tape in measuring the depth of liquid in tanks, sounding in hydrographic surveys, cross sectioning streams, and the like.

Another object is to provide such a device that will be compact, adaptable to any shape, quickly and easily adjusted to and removed from the tape, accurate, with no springs to wear out and no springs to adjust, and adapted to have the bottom thereof positioned flush with the end of the tape.

With the above and other objects in view, my invention consists in the combination and arrangement of parts hereinafter described and claimed, and more particularly illustrated by the embodiment shown in the accompanying drawings, in which

Figure 1 is a perspective elevation of my invention in connection with a metallic tape;

Figure 2 is a sectional view through my invention along the line 2—2 of Figure 7;

Figure 3 is an interior elevation of one of the halves of the invention, the other half being substantially similar;

Figure 4 is an elevation of one of the inserts;

Figure 5 is a sectional view similar to Figure 2 showing the inserts in use therein;

Figure 6 is a bottom plan view of the invention;

Figure 7 is a top plan view of my invention.

In the embodiment shown in the drawings, the invention is designed for use with a fifty foot metallic tape of any standard make; however, an insert is provided whereby the device may be used with any tape.

Upon examination of any standard fifty foot metallic tape, it will be found that the ring is attached to the tape end by a metal clevis approximately five-sixteenths of an inch in diameter. It is this clevis that is dependent

upon to lock the tape in the plumb bob as will hereinafter be described. My invention as described may be constructed of cast iron or brass, and in various weights and sizes.

Referring now more particularly to the drawings, I provide a body A having the shape of a frustum of a cone split along its longitudinal center line into two equal portions as at 1 and 2. The portion 1 has fastened thereto the spring clips 3 adapted to engage the depressions 4 provided in the portion 2. Two small dowel pins 5 are posi-

tioned in the portion 1 and adapted to engage the holes 6 provided in the portion 2, whereby the said portions 1 and 2 are adapted to exactly register with one another and held together by means of the spring clips 3 aforesaid.

Corresponding recesses 7 are provided in the inner faces of the portions 1 and 2, the said recesses extending longitudinally the plumb bob. A transversely extending semi-circular recess 8 is provided in each portion and communicates with the longitudinal recesses 7. The said semi-circular recesses 8 are so positioned in the plumb bob with respect to the bottom thereof that the clevis 9 of a metallic tape 10 will fit into the said recesses 8 and the end bar 11 of the ring 12 will come flush with the bottom 13 of the plumb bob A. The said bottom 13 of each portion 1 and 2 of the plumb bob A is provided with the recess 14, so that the plumb bob when resting upon a flat surface (not shown) will rest only upon the outside perimeter 15 and a small portion, as at 16, at the center around the slot 17 formed by the corresponding recesses 7 when the two portions of the plumb bob are fastened together.

Referring to Figures 4 and 5, an insert is shown for use when other than a standard metallic tape is used. Two similar pieces of metal or inserts 18 are provided adapted to fit into the corresponding recesses 7; the said inserts 18 have formed on one side the ribs 19 adapted to engage the semicircular recesses 8; on the other side of the inserts is provided a recessed channel 20 provided with the transverse groove 21. The inserts are fastened to the two portions of the plumb bob by means of screws as at 22 so that the channels 20 and transverse grooves 21 of the two inserts register with one another whereby a tape 23 may be positioned in the said channels and the end 24 of the tape positioned in the grooves 21.

I claim:

1. In a plumb bob adapted for use with a metallic tape, a body formed in the shape of a frustum of a cone split along its longitudinal center line into two portions; each of said portions having corresponding recesses adapted to receive said tape; and means for fastening the portions together.

2. In a plumb bob adapted for use with a metallic tape provided with a metal clevis; a body formed in the shape of a frustum of a cone split along its longitudinal center line

into two portions; each of said portions having corresponding recesses adapted to receive said tape and also having transverse semi-circular recesses communicating with said 5 longitudinal recesses and adapted to receive said clevis; and means for fastening the portions together.

3. In a plumb bob adapted for use with a metallic tape, a body formed in the shape of a frustum of a cone split along its longitudinal center line into two portions; each of said portions having corresponding recesses adapted to receive said tape; means for fastening the portions together; the bottom of 10 said portions having arcuate recesses whereby the plumb bob is adapted to rest only up on its perimeter and its central part.

4. In a plumb bob adapted for use with a metallic tape provided with a metal clevis; a 20 body formed in the shape of a frustum of a cone split along its longitudinal center line into two portions; each of said portions having corresponding recesses adapted to receive said tape and also having transverse semicircular recesses communicating with said lon- 25

itudinal recesses and adapted to receive said clevis; means for fastening said portions together; the bottom of said portions having arcuate recesses whereby the plumb bob is adapted to rest only upon its perimeter and 30 its central part.

5. In a plumb bob adapted for use with a tape, a body formed in the shape of a frustum of a cone split along its longitudinal center line into two portions; each of said 35 portions having corresponding longitudinal recesses and also having transverse semicircular recesses communicating with said longitudinal recesses; a pair of corresponding inserts adapted to engage said longitudinal 40 recesses; semicircular ribs positioned on the outer faces of said inserts adapted to engage said transverse recesses in the plumb bob; the inner faces of said inserts being adapted to engage said tape; and means for fastening 45 said portions together so as to enclose said inserts thereinbetween.

In testimony whereof I affix my signature.

FLOYD M. LEWIS.
